ULTRA HIGH FREQUENCY RECEIVING
SYSTEM

William S. Halstead, Huntington, N. Y., assignor
of one-third to John B. Brady, Washington,
D. C.

Application September 1, 1938, Serial No. 228,052

3 Claims. (Cl. 177—337)

This application is a continuation-in-part of my copending application Serial No. 42,703, filed September 28, 1935, for Radio traffic control system, now Patent No. 2,131,042, granted September 27, 1938.

My invention relates in general to directional ultra high frequency vehicle communications systems, and is more particularly concerned with means for receiving polarized ultra high frequency radio waves directed along a lane of traffic for vehicle control purposes.

It is a primary object of this invention to provide directionally-selective means for receiving ultra high frequency radio wave energy in a vehicle, said wave energy being transmitted along the lane of traffic on which said vehicle is proceeding by a directional ultra high frequency transmitter of the type shown in my copending application, supra, of which this is a continuation-in-part.

It is a further object of my invention to provide directionally-selective ultra high frequency receiving means which may readily be installed on vehicles for the purpose of effecting control of traffic signal indicators mounted within said vehicles.

It is an additional object of my invention to provide means for effecting connection of an ultra high frequency receiver with a second receiver designed for operation on lower frequencies, said connection effecting utilization of said second receiver for both ultra high and low frequency radio signals.

Other and further objects of my invention reside in the constructional and circuit arrangements for selecting a particular plane of polarization of a directional space-transmitted radio wave and for automatically effecting discrimination between ultra high frequency wave energy directed along different lanes of traffic as set forth in the specification hereinafter following and by reference to the accompanying drawings in which:

Figure 1 is a front elevational view of the instrument panel and windshield of a vehicle to illustrate a preferred disposition of a horizontal dipole antenna and ultra high frequency detector employed in the receiving system;

Fig. 2 is a side elevation of the same vehicle showing the horizontal dipole and detector unit illustrated in Fig. 1;

Fig. 3 is a circuit diagram of one form of ultra high frequency detector, amplifier and associated traffic signal indicating means employed in a vehicle to give audible and visual indication of

the character of an external traffic control signal;

Fig. 4 is a schematic block diagram showing connections between an ultra high frequency detector unit and a conventional low frequency broadcast receiver, the output circuit of the receiver being provided with visual means for indicating the character of the external traffic control signal;

Fig. 5 is a circuit diagram of a preferred form 10 of connection between an ultra high frequency detector unit and a low frequency broadcast receiver, showing means employed for selectively operating traffic signal indicating lamps installed within a vehicle and connections whereby automatic means are provided for removing a coupling connection between the ultra high frequency receiver and the audio amplifier of the broadcast receiver when a radio traffic signal is being received by the ultra high frequency 20 detector;

Fig. 6 is a circuit diagram of a modification of the signal lamp and the relay circuit of Fig. 5 showing the addition of chime signals to the indicator system;

Fig. 7 is an elevational view of a portion of 25 the interior of a locomotive cab equipped with an ultra high frequency receiver and a dipole antenna having means for rotating it through an angle of ninety degrees for selectively receiving horizontally or vertically polarized wave 30 energy;

Fig. 8 is a schematic block diagram of an ultra high frequency traffic signal receiver employing a detector, amplifier, loud speaker, and a plurality 35 of electric wave filters, each filter having an associated signal light for selective energization in accordance with the character of an external signal; and

Fig. 9 is a circuit diagram of an ultra high 40 frequency receiver and associated electric wave filters of the electro-magnetic type for effecting selective operation of signal lights installed in the locomotive cab.

Referring to the drawings in detail, wherein 45 like reference characters indicate corresponding parts throughout the several views, each form of the invention illustrated herewith embodies quasi-optical radio wave receiving means such as provided by an ultra high frequency detector 30, Fig. 1, combined with a directionally selective antenna such as a horizontal dipole 66 to effect 50 reception of radio traffic control signals from a directional transmitter of the type shown in my copending application, supra, of which this is a continuation-in-part.

In the particular embodiment of the invention shown in Fig. 1 in which the ultra high frequency receiver is installed on a vehicle, a horizontal dipole antenna 66 is mounted on the outside of the vehicle at a point just above the windshield 102 which location has a distinct advantage in that the dipole is substantially in line of sight relationship to the transmitting dipole, regardless of the presence of other vehicles of moderate height on the traffic lane ahead. As pointed out heretofore, metallic structures reflect ultra high frequency radiant energy and act as a shield through which the wave energy does not effectively penetrate. It is desirable therefore to mount the receiving dipole at such a height that the presence of the steel body of a preceding vehicle, will not prevent the reception of the radio traffic control signal. Moreover, the location as described has an additional advantage in that the shielding effect of the body proper reduces signal pick-up from an ultra high frequency transmitter which has been passed. The detector housing 67, Fig. 1, shown in the drawings with its front cover removed, may be installed either on the interior or exterior of the vehicle at a point substantially adjacent to the mid-point of the dipole as indicated so that short leads between the dipole and the input circuit of the detector are effected. High frequency choke coils 31 and 32, Fig. 3, in the anode and grid leads of the detector circuit are also included in the housing of detector unit 67. The output circuit of detector tube 30 and the power supply leads are placed in a shielded cable, indicated by dotted lines in Fig. 1. The cable makes connections with the input and power supply terminals of an amplifier 75. Visual signal indicating devices such as a red lamp 104 and a green lamp 105, connected to suitable frequency discriminating devices such as electric wave filters, not shown in Fig. 1 but described and illustrated herein-after, are located in proximity to the instrument panel of the vehicle. The lights are installed on or near the instrument panel in the driver's line of vision. A loud speaker 68 is disposed behind the instrument panel or in any other effective location to provide audible indication of the character of the traffic signal as described in my copending application, supra.

A circuit diagram of one form of ultra high frequency receiver with visual and audible signal indicators is shown in Fig. 3. The parallel rod plate and grid leads of detector tube 30 are connected to the ends of dipole 66 as shown, or by inductive coupling as illustrated in Fig. 9. A variable condenser, shown in dotted lines may be used if aperiodic tuning is not desired. Radio frequency chokes 31 and 32 are inserted in series in grid and plate leads. Resistor 33 is connected in series with the grid lead as illustrated, one side of this resistor being grounded in conventional manner. The cathode of the detector tube is grounded and a small by-pass condenser 34 is connected between the plate circuit and ground. The plate circuit is completed through the primary winding of coupling transformer 35 which is connected to a source of plate potential. The filament is connected to a storage battery or other filament supply source. The secondary winding of the amplifying transformer 35, is connected in conventional manner to a volume control 107 such as a potentiometer and thence to control grid and ground of audio frequency amplifying tube 106. The output circuit of tube 106 comprises an output transformer

108 having a plurality of windings to which are connected a loud speaker 68 and several frequency discriminating devices such as electric wave filters or tuned amplifiers 109 and 110. The output circuits of the filters or tuned amplifiers are connected to visual signal indicators, such as neon lamps 104 and 105, or relay-controlled lamps such as shown in Figs. 5, 6 and 9. Each filter or tuned amplifier is tuned to pass wave energy having a predetermined frequency which is correlated with definite traffic control functions as described in my copending application, supra. Thus the red light 104 will be controlled only by wave energy of frequency F1 and the green light 105 will be energized only when the ultra high frequency carrier is modulated by wave energy of frequency F2. Both signals will be heard on the loud speaker, 68. Although apparatus is shown for use with control waves of audio frequency nature, it is obvious that the ultra high frequency carrier can be modulated by a plurality of control signals of the radio frequency type if desired. In this event modulating control frequencies above 10,000 kilocycles may be employed together with amplifying and frequency discriminating equipment designed for use with radio frequency rather than audio wave energy.

A modification of the ultra high frequency receiving and signal indicating system is shown in the schematic diagram of Fig. 4 in which the output circuit of the ultra high frequency detector 67 is coupled to the audio frequency circuit of a conventional form of broadcast receiver 111 in such manner that the loud speaker of the broadcast receiver may be employed in making audible the demodulated ultra high frequency signals. Since the signal delivered to the broadcast amplifier by the ultra high frequency receiver will be heard from loud speaker 68 regardless of the broadcasting wavelength to which the radio frequency circuits of the broadcast receiver may be tuned, such as a receiver will, without tuning adjustments on the part of the driver provide both the customary programs from broadcasting stations and occasional highway traffic instructions, warnings and radio traffic control signals from directional ultra high frequency roadside transmitters of the type described in my Patent No. 2,131,042, supra. As each section of the composite receiver has its own volume control adjustment, the signal level of either type of communication can be controlled independently of the other. By connecting the input circuits of suitable frequency discriminating devices, such as sharply tuned electric wave filters or amplifiers 109 and 110, to the output of the broadcast receiver, as shown in dotted lines, selectively operated visual signal indicators such as neon lamps 104 and 105, may be visibly actuated by the output voltage of filters 109 and 110 when a sustained control signal is received to give indication of the character of the traffic lights ahead of the car.

In the preferred form of connection between the receivers shown in Fig. 5, the output circuit of ultra high frequency detector 67 is connected through a shielded cable to the primary winding of a coupling transformer 155. The secondary winding of the transformer is connected in conventional manner as shown, to a volume controlling potentiometer 156 whose arm is connected to the control grid of amplifying tube 157. The plate of the tube 157 is supplied with the proper D. C. potential by means of wire 158

which is connected to the plate voltage supply lead of the broadcast amplifier. Signal voltage coupling means between the plate circuit of tube 157 and the input circuit of the power amplifier tube 159 of the broadcast receiver is provided by coupling condenser 160, inserted in lead 161 which is connected to the grid circuit of the power amplifier through switch 162 as shown. Signal voltage from the ultra high frequency detector is also supplied to the input circuits of two tuned amplifiers 163 and 164 by connection with the primary winding of coupling transformer 155 as illustrated. The output circuit of amplifier 163, which is tuned to pass sustained wave energy of frequency F1 correlated with the traffic control "stop" signal, is connected to the tuned winding 165 of a relay as shown. The armature 166 of the relay is connected with a source of E. M. F. such as car battery 167. The fixed contact 168 of the relay is connected to one side of the filament of an electric lamp 169, the other side being connected to the storage battery as illustrated. Any conventional pilot light color disc or lens, not shown, may be placed in front of lamp 169 to give it the red "stop" signaling characteristic. The red light can be energized only when sustained wave energy of frequency F1 is received since wave energy having other frequencies will not develop sufficient voltage in winding 165 to move armature 166 to contact 168. Similarly, the output circuit of tuned amplifier 164 is connected to winding 170 of the second relay as shown. The armature 171, is connected to the storage battery, and the fixed contact 172 is connected to one side of the filament of green lamp 173 so as to energize the filament when the armature is moved to the contact. Both relays are preferably of the slow-response type to effect control of the lights only when sustained control signals are received. Speech or other modulating signals will not effect their operation because of the lack of a long-sustained tone of a particular frequency. However, speech or other modulated wave energy will be applied to the control grid of power amplifier 159 of the broadcast receiver and will operate loud speaker 174.

In the arrangement of Fig. 5 thus far described, it is obvious that the light-control signals of frequency F1 and F2 will be heard from loud speaker 174. Since this may not be desirable under many circumstances, automatic means is provided by which the signal coupling circuit between the ultra high frequency and broadcast receivers is disconnected as long as the sustained light control signals are being received. Thus if a broadcast program is being received, the signal lights may be operated in the car without interference from the sustained control signals. This function is effected by the provision of an additional contact arm 175 on the armature 166, and a similar additional arm 176 on armature 171. Fixed contact 177 is normally in position against arm 175, and contact 178 is normally touching arm 176. The contacts and arms of the two relays are in series connection as shown so that if either relay is operated, the auxiliary circuit will be broken. The auxiliary circuit is connected across switch 162 as shown so as to close or open the coupling circuit between the ultra high frequency and broadcast receivers. Normally, when no sustained control signal is received the relays are in the inoperative position with the auxiliary contact arms 75

closing the circuit between the ultra high frequency and broadcast receivers. Thus speech modulated highway instructions and warnings from roadwise ultra high frequency transmitters (not shown) may be made audible to the driver by loud speaker 174. As soon as the sustained control signal of frequency F1 or F2 is received either one of the relays will close and the control signal will be cut from the broadcast circuit. Since the relays are of the slow acting type, the control tone will be heard for a moment before the selected relay operates, thus giving the driver a brief aural indication of the character of the signal as previously described in my Patent No. 2,131,042, supra. Fig. 6 shows an automatic disconnecting arrangement similar to that in Fig. 5 with the addition of small single-stroke chimes 179 and 180 connected to the red and green light circuits respectively, the chimes being employed to give aural traffic signal warnings where the sound of the control signals from the loud speaker is not effective.

A preferred arrangement of ultra high frequency receiving apparatus suitable for use in connection with the transmitting system of Figs. 25 to 28 of my copending application Serial No. 42,703 now Patent No. 2,131,042, granted September 27, 1938, is illustrated in Figs. 7 to 9 inclusive. The adjustable receiving dipole, shown in horizontal position at 135, Fig. 7, is connected to an ultra high frequency detector unit 136, both units 135 and 136 being installed near the top and at the front of the cab of a locomotive as indicated. The demodulated output of detector unit 136 is supplied, as schematically shown in Fig. 30, to the input circuit of an amplifier 137. The output of amplifier 137 is connected to a loud speaker 138, as shown, and to the input circuits of electrical wave filters 139, 140 and 151, preferably of the tuned reed type, each tuned to a predetermined signal control frequency as F1, F2 and F3, respectively. The output circuits of the filters 139, 140 and 141, are connected to signal lights 142, 143 and 144, respectively, installed in proximity to the instrument board of the locomotive. Means are thus provided by which a plurality of control signals each having a different predetermined frequency value, such as F1, F2, F3, as well as telephonic signals emitted by an ultra high frequency transmitter may be received in the cab of the locomotive by ultra high frequency detector 136 and thereafter separated by suitable filter devices into the constituent modulating control signals of frequency F1, F2 and F3 to effect selective visual energization of signal lights of different colors as well as audible reception of the traffic control and speech signals.

A circuit diagram of such an ultra high frequency receiving and signal indicating system is shown in Fig. 9 in which the output circuit of ultra high frequency detector unit 136, similar to that of Fig. 3, is connected to the primary windings of amplifying transformer 35 disposed in series in the positive plate battery lead. The secondary windings of transformer 35 are connected in well known manner to the input circuit of amplifier 137 whose output is connected to loud speaker 138 and the exciting coils of tuned reed filters 139, 140 and 141. The output coils of filters 139, 140 and 141 are connected to the input circuits of amplifiers 146, 147 and 148, respectively, whose respective output circuits are connected to the windings of relays 149, 150 and 151 respectively as shown. The ar-

mature contacts of relays 149, 150 and 151 are connected in series with electric lamps 142, 143 and 144 respectively, and a source of electric potential such as a storage battery 152, as shown. It is obvious that a time delay relay 28, and a power and brake control relay 29, may be added if desired to the circuit of red lamp 142 so as to bring the train to a stop should the brakes not be applied within a predetermined time after the stop signal has been energized.

The operation of the circuit shown in Fig. 31, is such that when an incoming modulating signal, having a control frequency F_1 , for example, is supplied to amplifier 137, the amplified signal is delivered to the exciting coils of tuned reed filters 139, 140 and 141. The metallic reed of filter 139 which is tuned to respond to predetermined signaling frequency F_1 , is forced into sustained vibration by the signal voltage in the exciting coils having frequency F_1 and a small voltage is thereby induced in the output coils of the filter unit in well known manner. The filtered output voltage is then supplied to the input circuit of amplifier 146 whose output voltage causes the actuation of relay 149 and the subsequent closing of the lighting circuit of red lamp 142 as may be understood readily from the circuit diagram. Since the tuned reeds of filters 140 and 141 are not forced into vibration by the applied signal voltage of frequency F_1 no voltage is induced in the output coils of these filters, and consequently no actuating current is supplied to relays 150 and 151 controlling the operation of lamps 143 and 144 respectively. It is further pointed out that a sustained electrical wave of given frequency such as F_1 is necessary to effect sufficient vibration of the reeds of the filter units to induce an operative voltage in the output coils of the filters. Thus reception of speech modulated signals of constantly varying frequency and amplitude does not interfere with the operation of the visual signal indicating means. Moreover, as tuned reed filters of the type described are extremely selective with regard to frequency response characteristics they thereby effect the rejection of all but the proper control signals in the output circuits of the filter units.

It will be recognized that the illustrative systems described herein are capable of considerable modification and rearrangement without departing from the spirit and scope of the invention, and it is therefore to be understood that the following claims embrace all such modifications and equivalent arrangements as may fairly be construed to fall within the scope of the invention.

What I claim as new and desire to secure by Letters Patent of the United States is as follows:

1. A radio receiving system for vehicles comprising in combination, a receiver tunable to one radio communications band, said receiver having an audio frequency amplifier and a loud speaker operated by said amplifier, a second receiver tunable to another radio communications band for receiving voice modulated and tone modulated

traffic control signals, means for coupling the output circuit of the second receiver to the input circuit of the audio frequency amplifier associated with said first receiver, and relay-controlled means operated by said tone modulated traffic control signals received by the second receiver for automatically disconnecting said coupling means from the output circuit of said second receiver, said relay-controlled means being non-responsive to said voice modulated traffic control signals which are reproduced in said loud speaker.

2. A radio receiving system for vehicles comprising in combination, a radio receiver tunable to one radio communications band, a second receiver tunable to another radio communications band for receiving voice modulated and tone modulated traffic control signals, tone frequency discriminating means connected to an output circuit of said second receiver, a relay controlled by tone signal energy of predetermined frequency passed by said frequency discriminating means, a signal coupling connection between an output circuit of said second receiver and an input circuit of said first receiver, said coupling connection being removable by the selective operation of said relay as determined by received tone signal energy of predetermined frequency, said relay being inoperative by said voice modulated signals which are reproduced in said loud speaker.

3. A radio receiving system for vehicles comprising, in combination, a non-directional antenna mounted on a vehicle, a radio broadcast receiver tunable to one radio communications frequency band coupled with said antenna and including an audio frequency amplifier and a loud speaker operated by said amplifier, a directionally selective antenna mounted on the vehicle for receiving voice modulated and different tone modulated traffic control signals propagated towards said vehicle, a radio traffic control receiver operative in another radio communications frequency band coupled with said directionally selective antenna, means for coupling the output of said radio traffic control receiver to the input circuit of the audio frequency amplifier associated with the first said broadcast receiver, electric wave selectively responsive means and indicating means connected to said traffic control receiver and operative in accordance with a particular tone modulated traffic control signal received by said traffic control receiver, each of said tone modulated traffic control signals being correlated with traffic conditions for vehicle traffic control purposes, and relay switch means operated by said selectively responsive means for automatically disconnecting said coupling means from the output circuit of said traffic control receiver whereby said tone modulated signals are not reproduced by said loud speaker, said relay switch means being inoperative by said voice modulated signals whereby said voice modulated traffic control signals are reproduced in said loud speaker.

WILLIAM S. HALSTEAD.
